WISCONSIN.

IRONING-BOARD.

1,159,995.

Specification of Letters Patent.

Patented Nov. 9, 1915.

Application filed October 9, 1914. Serial No. 865,923.

To all whom it may concern:

Be it known that we, KATHERINE RILEY and GEORGE TIMLIN, citizens of the United States, residing, respectively, at Reedsburg and Cazenovia, in the counties, respectively, of Sauk and Richland, State of Wisconsin, have invented a new and useful Ironing-Board, of which the following is a specification.

10 The device forming the subject matter of this application is an ironing board embodying, in combination with the usual platform, a pivotally mounted sleeve board, adapted when not in use to be swung beneath the platform.

One object of the present invention is to provide novel mechanism for holding the sleeve board in a folded position beneath the platform.

20 Another object of the invention is to provide novel means whereby the sleeve board is operatively connected with the platform and is held in adjusted positions with respect thereto.

25 It is within the scope of the invention to improve generally and to enhance the utility of devices of that type to which the present invention appertains.

With the above and other objects in view 30 which will appear as the description proceeds, the invention resides in the combination and arrangement of parts and in the details of construction hereinafter described and claimed, it being understood that 35 changes in the precise embodiment of the invention herein disclosed can be made within the scope of what is claimed without departing from the spirit of the invention.

In the accompanying drawing: Figure 1 40 shows the invention in vertical longitudinal section, the parts appearing in the positions which they will assume when the device is in use; Fig. 2 is a bottom plan showing the structure folded up; Fig. 3 is a perspective 45 delineating the angular arm which forms a part of the sleeve board; Fig. 4 is a fragmental bottom plan of that end of the platform to which the sleeve board is pivotally attached; Fig. 5 is a fragmental cross section 50 through the platform portion of the device and showing the mounting of the slides, one of which co-operates with the sleeve board; and Fig. 6 is a perspective delineating the U-shaped strip whereby the sleeve board is

pivots and adjustably connected with the 55 platform.

The ironing board herein disclosed embodies a platform 1 provided adjacent one end with depending angle brackets 2, the vertical flanges of which are provided with 60 a plurality of openings, adapted to receive for adjustment, pivot elements 4 forming mountings for the upper ends of main legs 5 connected adjacent their lower ends by a terminal rung 6 and connected intermediate 65 their ends by a rung 7 preferably taking the form of a flat strip. Mounted in the main legs 5 intermediate their ends are pivot elements 8 supporting the intermediate portions of auxiliary legs 9 connected adjacent 70 their lower ends by a rung 10 and connected adjacent their upper ends by a cross strip 11.

In order to fold up the legs 5 and 9 from the positions shown in Fig. 1 to the positions shown in Fig. 2, the upper ends of the legs 75 9 are carried to the right as indicated by the reference arrow A, the lower ends of the legs 9 moving to the left as indicated by the reference arrow A and the lower ends of the legs 5 following the reference arrow B. By this 80 operation, the cross strip 7 which connects the main legs 5 will be disposed against the under face of the platform 1. A latch 12 is slidably mounted within the contour of a keeper 14 secured to the lower face of the 85 platform, and this latch 12 is adapted to coact with the part 7 to hold the legs folded, as clearly shown in Fig. 2. Ratchet plates 16 are secured to the under face of the platform 1 adjacent one end thereof, the plates 90 16 having teeth 15. When the table is set up as shown in Fig. 1, the cross strip 11 is engaged with certain of the teeth 15 on the ratchet plates 16. Disposed between the ratchet plates 16 and secured to the under 95 face of the platform 1 is a plate 18 having spring teeth 17. The cross strip 11, as shown in Fig. 1 is engaged upon the one side by the teeth 15 of the ratchet plates 16 and is engaged upon its opposite side by one 100 tooth 17 on the plate 18. Thus, a disengagement of the cross strip 11 from the ratchet teeth 15 is prevented.

Attached to one end of the platform 1 is a pair of U-shaped pivot strips 19, one of 105 which is shown inverted in Fig. 6. The pivot strips 19 depend below the platform 1 and are provided at the ends of their arms

with feet 20 and 20', secured respectively, to the upper and lower surfaces of the platform 1. A guide strip 21 extends transversely of the platform 1 adjacent one end 5 thereof, the guide strip 21 passing across the feet 20' of the pivot strips 19. Securing elements 22 connect the guide strips 21 with the platform 1 and certain of these securing elements pass through the feet 20' of the 10 strips 19 to aid in holding the same on the platform. If desired, other securing elements indicated at 23 may pass through the feet 20' and enter the platform 1. Disposed parallel to the guide strip 21 is a guide strip 15 24 united by means of securing elements 25 with the platform 1, one end of the guide strip 24 being united by means of a securing element 26 with some accessible portion of the table, for instance, the depending flange 20 of one of the pivot brackets 2. Mounted to slide beneath the guide strips 21 and 24 to one side of the U-shaped pivot strips 19 is a flat plate constituting a flatiron holder 27. A support in the form of a plate 28 is 25 mounted to slide beneath the strips 24 and 21 and is adapted to be pushed outwardly between the U-shaped pivot strips 19, it being noted at this point that the longitudinal edges of the feet 20' of the U-shaped strips 30 19 act as guides, directing the right line movement of the support 28. At their ends, the iron holder 27 and the support 28 are provided with projecting lips 29. One set 35 of these lips is adapted to coact with the guide strip 24 to prevent the parts 27 and 28 to be pushed outwardly to too great an extent, the other set of lips 29 being adapted to coact with the guide strip 21, as clearly shown in Fig. 4, to prevent the elements 28 and 27 from being pushed inwardly beyond a predetermined point.

The invention includes a sleeve board denoted by the numeral 30. To one end of the sleeve board is attached an angular arm 31 45 in the form of a plate, the plate 31 having a flange 31^a which preferably is recessed into the sleeve board 30 adjacent one end thereof and is secured thereto. Projecting from the plate or arm 31 adjacent to the other end 50 thereof is an outstanding flange 32, having openings 32^a. These openings 32^a receive the U-shaped pivot strips 19. When the sleeve board 30 is swung beneath the platform 1, the sleeve board may be held in place 55 by means of a latch 33 mounted to slide beneath a keeper 34 on the lower face of the platform 1, although, as hereinafter described, another means is provided for holding the sleeve board in place when the device is folded up as shown in Fig. 2.

Journalized for rotation in bearings 35 on the under face of the sleeve board 30 is a shaft 36 carrying legs 37 and provided with an arm 38 disposed at right angles to the 60 legs.

Mounted to slide beneath a keeper 41 on the under face of the sleeve board 30 is a latch 40 which is adapted to coact with the arm 38 on the shaft 36 to hold the legs 37 at right angles to the sleeve board 30 and to the platform 1 as clearly shown in Fig. 1. 70

The operation of the structure is as follows: In order to fold up the device, referring to Fig. 1, the sleeve board 30 is swung around to the right and is disposed beneath the platform 1, the flange 32 of the arm 31 riding downwardly on the U-shaped pivot strips 19. Owing to the fact that these strips 19 are substantially equal in depth to the height of the flange 31, the sleeve board 30 may be swung beneath the platform 1 and be disposed approximately parallel thereto, the arm 31 standing at right angles to the platform. When the table is set up as shown in Fig. 1, but when the sleeve board 30 lies beneath the platform, the sleeve board may be held in place by means of the latch 33. When however, the legs 9 and 5 are folded up as shown in Fig. 2, the cross strip 11 which connects the legs 9 extends across the sleeve board 30 and engages the same, as will be obvious from Fig. 2. Now, if the latch 12 is engaged with the intermediate rung 7 of the main levers 5, the cross strip 11 will be held in place 95 transversely of the sleeve board 30.

When the table is set up as shown in Fig. 1, the arm 31 on the sleeve board is upheld by the upper feet 20 of the pivot strips 19 as clearly shown in Fig. 1. The latch 40 100 is engaged with the arm 38 to hold the legs 37 at right angles to the sleeve board 30 and the platform 1 thereby to support the sleeve board from the platform, as Fig. 1 will show. When a support for a flat iron 105 is desired, the holder 27 is drawn out.

At times it is desirable to swing back the sleeve board 30 into the dotted line position shown in Fig. 1 and to maintain the sleeve board in an out-of-the-way, yet convenient and upstanding relation to the platform 1. Under such circumstances, the support 28 is drawn outwardly and engages the arm 31 to uphold the sleeve board.

Having thus described the invention, what 115 is claimed is:

1. A sleeve ironing device comprising a sleeve board support; a depending U-shaped pivot strip attached to one end of the sleeve board support; a sleeve board; an arm secured to the sleeve board and projecting therefrom at an angle to the board, the arm having an opening through which the strip passes; and a leg on the board and adapted to engage the sleeve board support; the arm being slidable upon the strip and the strip being substantially equal in depth to the height of the arm, whereby when the sleeve board is swung beneath the sleeve board support, the board may stand approximately 120 125 130

parallel to the platform and the arm may stand substantially at right angles to the sleeve board support.

2. In a sleeve ironing device, a sleeve board support; a sleeve board disposed above the support and provided with an angularly disposed arm; means for pivotally connecting the arm with one end of the support; and a slide mounted upon the support, 5 the slide being adapted to be advanced, to engage the arm, thereby to hold the sleeve board in an upstanding position with respect to the support.
3. In a sleeve ironing device, a sleeve 10 board support; a sleeve board; an arm forming a pivotal connection between the sleeve board and the support; a shaft journaled for

rocking movement on the sleeve board; a leg carried by the shaft; an extension carried by the shaft and disposed at an angle 20 to the leg; and a movable locking device on the sleeve board and adapted to coact with the extension to hold the leg at an angle to the sleeve board, the leg being adapted to engage the support to hold the sleeve board 25 spaced from the support.

In testimony that we claim the foregoing as our own, we have hereto affixed our signatures in the presence of two witnesses.

KATHERINE RILEY.
GEORGE TIMLIN.
